ATTORNEY.

UNITED STATES PATENT OFFICE

WILLIAM Y. CASTONGUAY, OF DETROIT, MICHIGAN

ART OF DESTROYING MOTH WORMS, ETC.

Application filed July 2, 1930. Serial No. 465,414.

The primary object of my invention is to provide an improved method and apparatus whereby moths, moth worms and the like in furniture, clothing and other articles can be effectively and quickly exterminated with little trouble and expense.

A further object is to provide an apparatus of the above kind which is self-contained and self-propelled so that it can be run by its own power to the premises where the articles to be treated are stored or in use, thereby avoiding much of the time, trouble and expense involved in the present common practice of packing the articles, transferring them to an establishment for unpacking and treatment, and then re-packing and returning the articles to the original premises, where they are again unpacked and stored or placed in use.

I have discovered and demonstrated that by subjecting furniture, clothing or other articles to the action of carbon monoxide gas within a closed or relatively air-tight chamber, any moths, moth worms, moth eggs and the like in or on such articles will be effectively destroyed. I have further discovered and demonstrated that the exhaust gases from an internal combustion engine contain sufficient carbon monoxide gas for this purpose, and hence my invention may find practical embodiment in a motor vehicle provided with a chamber into which may be placed the articles to be treated, and means for conveying the exhaust gases from the internal combustion engine, which drives the vehicle, into such chamber. In order to insure complete filling of the chamber with the exhaust gases without danger of sufficient back pressure on the engine to render the latter inoperative, I preferably provide the chamber with a relief valve for automatically permitting controlled escape of the exhaust gases to the atmosphere when the said gases attain a predetermined relatively low pressure in the chamber. This insures operation of the apparatus with maximum efficiency and destruction of the moth worms and the like in the shortest possible time.

Further objects and advantages will be made apparent in the following description

when considered in connection with the accompanying drawings, in which:

Figure 1 is a view, partly in side elevation and partly broken away and in longitudinal section, of an apparatus embodying the present invention.

Figure 2 is an enlarged fragmentary rear elevational view thereof.

Figure 3 is an enlarged vertical transverse section on line 3—3 of Figure 1.

Figure 4 is an enlarged horizontal section on line 4—4 of Figure 2; and

Figure 5 is a detail of the means for selectively effecting discharge of the exhaust gases to the fumigating chamber or to the exhaust muffler of the vehicle.

A vehicle used for the purpose I have indicated is provided with a relatively closed or air-tight body or fumigating chamber 5 having doors 6 through which the articles to be treated may be introduced and removed. The vehicle is driven by an ordinary internal combustion engine 7 having an exhaust pipe 8 leading to the usual muffler 9. A branch pipe 10 leads from the intermediate portion of the exhaust pipe 8 into the front portion of the chamber 5 and has a suitable filter 11 interposed therein for relieving the exhaust gases of obnoxious foreign matter which may have a detrimental effect on the articles placed in the chamber 5 for treatment. A valve 12 is arranged in the exhaust pipe 8 at the juncture of the branch pipe 10 therewith, whereby the exhaust gases may be diverted through the branch pipe 10 into the chamber 5 or to the muffler 9, at will. A lever 13 may be provided so that the valve 12 may be readily operated by the driver or attendant.

A vent 14 is preferably provided in the rear wall of the chamber 5 above the doors 6 and normally closed by a spring-seated relief valve 15. As shown, the valve 15 carries a stem 16 whose inner end is pivoted to a lever 17 and which is in turn pivoted at one end to a bracket 18 mounted on the wall of chamber 5 at one side of the vent 14. A pressure-motor has its casing 19 mounted in an opening in the wall of the chamber 5, and one side of its diaphragm 20 exposed to the

interior of the chamber 5. The diaphragm 20 is yieldingly pressed inwardly by a spring 21 surrounding a stem 22 which slidably projects outwardly through a bushing 23 adjustably threaded in the outer end of the casing 19. The stem 22 bears against the diaphragm 20, and the spring 21 is interposed between a collar 24 on the stem 22 and the inner end of the bushing 23. A handle 10 and pointer 25 is provided on the outer end of the bushing 23 for convenience in adjusting the latter to place the spring 21 under the desired compression, a suitable dial 26 being provided on the outside of the chamber 5 to cooperate with the handle and pointer 25 so that the adjustments may be accurately and readily made. The intermediate portion of lever 17 is pivoted to the diaphragm 20 as at 27, and it will be readily seen that when the exhaust gases in the chamber 5 reach a predetermined pressure, the diaphragm 20 will be pressed outwardly against the action of the spring 21 and the valve 15 will be opened. In this way, the 20 exhaust gases will be vented from the chamber 5 to the atmosphere until the pressure within said chamber is again reduced, thereby preventing such back pressure on the engine 7 as will cause the latter to "stall" or 25 become inoperative. As the permissible pressure varies under different operating conditions, the adjustment of the bushing 23 and of the compression of spring 21 will enable maintenance of maximum operating 30 efficiency at all times. Moreover, by keeping the gases under some pressure within the chamber 5, complete filling of the latter and thorough fumigation of the articles therein is insured in the shortest possible 35 time. However, the relief valve may take any one of many different forms, the one shown being merely illustrated by way of example.

In use, the vehicle is driven to the premises 40 where the articles to be treated are stored or in use, whereupon the articles are placed in the chamber 5 and the doors 6 closed. The valve 12 is then placed in the full line position of Figure 5 so as to cause the exhaust 45 gases from the engine 7 to discharge through pipe 10 into the chamber 5, the gases being automatically vented from time to time when the pressure in such chamber becomes sufficiently high to cause the valve 15 to open. 50 When the articles have been treated for the required period of time, the valve 12 is shifted to the dotted line position of Figure 5 and then the doors 6 are opened and the articles removed. Care will of course be required to avoid the gases when opening the doors 6 unless they are previously scavenged from the chamber 5 by suitable means. I have found that articles so treated will have the moth worms and the like thereof effectively and quickly destroyed due to the de-

structive effect of the exhaust gases, the most effective killing element or ingredient of which is carbon monoxide gas. While this element has long been known to be a destroyer of insect and animal life, its efficiency in 70 destroying moth worms, moth eggs and the like has not been previously discovered and appreciated, so far as I am aware. Moreover, the moth eggs and worms are the most difficult and necessary things to destroy in 75 ridding articles of pests preparatory to moth-proofing them, the moth fly and other actual insects being very easy to destroy and having little or no destructive action on the articles.

The invention contemplates such changes and modifications as may fairly fall within the scope of the appended claims.

What I claim as new is:

1. A portable apparatus for destroying moth worms and the like in furniture, clothing and other articles, comprising a motor vehicle having an internal combustion driving engine, a relatively closed chamber supported on said vehicle to receive the articles to be fumigated, means to conduct the exhaust gases from the engine into said chamber, means to filter the exhaust gases prior to discharging the same into said chamber, a vent pipe supported by one wall of the chamber, a normally closed spring seated relief valve therefor, and means for automatically opening said valve including a yieldably supported pressure actuated diaphragm arranged within the chamber. 95

2. A portable apparatus for destroying moth worms and the like in furniture, clothing and other articles, comprising a motor vehicle having an internal combustion driving engine, a relatively closed chamber supported on said vehicle to receive the articles to be fumigated, means to conduct the exhaust gases from the engine into said chamber, means to filter the exhaust gases prior to discharging the same into said chamber, a vent pipe supported by one wall of the chamber, a normally closed spring seated relief valve therefor, including a stem, a horizontally arranged lever pivoted on one wall of the chamber and pivotally connected with said stem, and a yieldably supported pressure actuated diaphragm located within the chamber and connected with the lever at a point in its length, to automatically open said valve at a predetermined pressure within the chamber. 115

In testimony whereof I affix my signature.

WILLIAM Y. CASTONGUAY.
